M. MEGRDCHIAN

DRIVING REIN

Filed Dec. 12, 1923

INVENTOR
Moosh Megrdchian
BY
Francis C. Schubner,
ATTORNEY

UNITED STATES PATENT OFFICE.

MOOSH MEGRDCHIAN, OF FRESNO, CALIFORNIA.

DRIVING REIN.

Application filed December 12, 1923. Serial No. 680,108.

To all whom it may concern:

Be it known that I, MOOSH MEGRDCHIAN, a citizen of Armenia, and resident of Fresno, in the county of Fresno, and the State 5 of California, have invented a new and useful Improvement in Driving Reins, of which the following is a specification.

My invention relates to a harness attachment, and more particularly to driving 10 reins.

The primary object of my invention is the construction of driving reins which will tend to direct the horses to travel in a straight line. Other objects will be herein- 15 after set forth.

I accomplish these objects by means of my invention hereinafter described and illustrated on the accompanying drawing in which Figure 1 shows an arrangement of 20 the driving lines as attached to the bits of two bridles. Figure 2 is a special kind of sliding snap hook to be used with the reins.

In said drawing, 4 and 5 are the main lines, which are attached to rings 7 and 8 25 on bits 3 and 6; and 9 and 10 are check lines which branch from the main lines 4 and 5 at a point between the ends thereof. The check lines have a slit 11 lengthwise through the middle. A snap hook 12 is provided, having an eye 13 through which the 30 check lines 9 and 10 pass. A projection or finger 14 extends upward from the inside of the eye, and when the check lines are assembled, said finger slides within the slot 35 11 in the lines, and limits the length of the sliding adjustment of the check lines. Snap hook 12 has a rigid hook 14, and a spring tongue 15 which permits the hook to be engaged in a ring, the tongue 15 normally 40 keeping the hook from becoming disengaged. Hook 12 is assembled with the check reins 9 and 10 by having the check 45 reins slide lengthwise through the eye 13, and with the finger 14 engaging a slot in the line. The hooks 12 should be snapped to the inside rings 17 and 18 of bits 3 and 6. The ends of check lines 9 and 10 are attached at their ends to a common ring 19.

It is noted that by this arrangement, by

pulling the main line 4, the bits 3 and 6 50 will be pulled toward the left, and by pulling the line 5 said bits will be pulled toward the right. If either of the horses move in other than a straight forward direction the pressure on the bit caused by the inside 55 line extending between the two bits, will prevent the horse from going in the direction in which it started.

I claim as new and ask for Letters 60 Patent:

1. Driving reins consisting of two main lines having branches attached thereto forming a Y, one of said branches on each main line being adapted to be attached to a ring of a bit, and the other branches being adapted to be attached together, at the ends thereof, and snap hooks adapted to slide on each of said branches and adapted to be attached to the rings of the bits, substantially as described. 65

2. Driving reins consisting of two main lines having branches forming a Y, the ends of the main lines being adapted to be attached to the outside ring of a bit, the ends of the other branches being attached together, sliding snaps on the branches which are attached together at the ends, means for limiting the distances said snaps can slide on said lines, said sliding snaps being adapted to be attached to the inside ring of said 70 bits, substantially as described. 75

3. In combination with a set of harness for two horses including a bit for each horse, a main line for each horse, the right line being attached at one end to the outside of the bit on the right side, and the left main line being attached to the outside of the bit on the left side, a branch line attached to the right line between the ends thereof having a sliding snap hook thereon adapted to 80 be attached to the inside of the bit on the right hand side, a branch line attached to the left line between the ends thereof having a sliding snap hook thereon adapted to be attached to the inside portion of the left 85 bit, and means at the ends of said branch lines adapted to attach said ends together. 90 95

MOOSH MEGRDCHIAN.
